(54) **LOOM, CARPET & RUG**

(76) Inventor: **William Bacon**

William Bacon.

The Schedule referred to in these Letters Patent and making part of the same containing a description in the words of the said William Bacon himself of his improvement in the machine for weaving rugs and carpeting. Be it known that William Bacon of the City and County of Philadelphia and State of Pennsylvania have invented an improvement in the machine for weaving rugs & carpeting which is described as follows. This machine consists of the following parts. 1st the frame 2nd the beams 3rd the top rail 4th the roller for the gears 5th the carriage for the gears 6th the shuttle 7th the pulleys for the rollers and gears. 1st the frame is made of four pieces of timber about 14 by 5 inches thick and 9 feet long. Two at each end. There are also two diagonal braces, one at each end of the same thickness and about 9 feet long. These last braces are connected and held together with the first mentioned pieces by other smaller braces placed near the bottom of the frame being all mortised and tenoned together to form the frame. Two pieces which brace the bottom of the frame serve also as carriage pieces for the treadles to work on, to be hereafter described.

2nd The beams may be made of any length and thickness to suit any sized carpet. In these beams are holes for inserting a pin for turning them with, holes for keeping them tight - the same as weaver's beams.

3rd The top rail is placed near the top of the frame over which the chair passes. It is made of any convenient size according to the breadth of the loom. 4th The roller for the gears is 30th inches diameter and from 2 to 3 feet long for one person to work at. There may be any number of rollers according to the size of the carpet.

part and number of persons employed—
5th the carriages for the gears in which the rolling
work consists of four pieces two at each end for keep-
ing the gears in a proper direction, are made of one
inch boards about 6 inches wide and four feet long.
6th The shuttles or needles are made similar to
common scine needles one for each colour and one
for the filling. 7th The fullers for the rods and gears
are five in number, two are placed on the top rail
two in the carriage of the gears for the treadles &
one on the bottom brace of the frame. Operation.
The chain is put on the gear beam in the usual way
over the top rail and then the gears and rods from
thence extended by lines to the cloth beam, the treadles
are pulled down, which open the chain and the filling
put in by the needles one thread at once. The plush
is then put in by the proper needles one for each
colour and worked to any required figure,
for this purpose the figure is first divided into small
squares and the colours are then worked so as to corre-
spond with the squares. In this way a carpet of any
size with a border worked in can be made to fit any
room, without seam, and to suit the fire places
and different scenes of the room. Invention claimed.

What I claim as my peculiar invention is the
construction of the before described machine by which
rugs and carpets can be worked to any size and fig-
ure without seam and to fit any room. For
a further illustration of my invention refer to the
model and drawing of the same deposited in the Patent
Office.

I witness whereof I have subscribed my name
A. B. at the City of Washington this 19th day of February
1830. Wm. J. Elliott, Thos. H. Garrison, William Bacon
